PAPER ROLL SUPPORT

Charles B. Blessing, Oakland, Calif., assignor to
Blessing Packaging Company, a corporation of
California

Application March 19, 1948, Serial No. 15,869

7 Claims. (Cl. 242—58)

1

This invention relates to garment baggers of the kind described in my copending application Serial No. 654,400, filed Mar. 14, 1946, now abandoned. More particularly this invention relates to various improvements in this type of machine as will appear hereinafter.

One of the objects of this invention is to improve the tubular paper feed in these machines. Another object is to facilitate the loading of the machine with rolls of tubular paper. Other objects than those specifically mentioned will appear from a consideration of the following specification and accompanying drawings, in which:

Fig. 1 is an elevation of my machine, showing certain details;

Fig. 2 is a frontal elevation of the loading and feeding mechanism;

Referring now to Fig. 1, the apparatus comprises a framework or first frame 10, into which there is fitted a roll 12 of tubular paper the web 14 of which is threaded over a roller 16 thence through a cutting, folding, and stapling apparatus at 18 and thence to the left in Fig. 1 and downwardly in the direction 20 to envelop a garment (not shown) partially, suspended by a coathanger 22 supported on upright post 24. Post 24 is readily removable so that the machine may be loaded as illustrated in Fig. 1.

The rolls of tubular paper are quite heavy. In order to facilitate loading the rolls into the machine, the apparatus comprises a roll support frame or rack 26 having a pair of opposite side members pivoted at one end on bracket 28 secured on floor 30 of the machine. Rack 26 comprises arms 26a and 26b provided with horizontally aligned pivotal supports 26c and 26d. The upper ends of arms 26a and 26b are provided with horizontally aligned facing pins 26e and 26f which receive a transverse member such as tube 26g with a close fit. The tubular paper of roll 12 is secured onto roll support means adapters 26h and 26k which in turn receive the pivoting supports 26c and 26d respectively. In the modification shown, the adapter 26h is not rotatable about the axis of the roll 12, with respect to the roll; both must rotate together for reasons presently to be pointed out.

In order to load the machine with a roll of tubular paper, the roll is placed in position 12' on the floor in front of the machine opposite the area between arms 26a and 26b. Rack 26 is now pivoted to the dotted line position. In this position the arms 26a and 26b are free to diverge sufficiently to allow pins 26c and 26d to

register with and enter the bearing holes in 26k and 26h. The tube 26g is now used as a handle to raise the roll to the full line position. Before completing the movement, the web 14 may be threaded under a feed controlling roller 32, which will presently be more particularly described, and held while rack 26 is forced to its full line position against stops 34 mounted on the walls of frame 10. Stops 34 form parts of cams 35 which diverge forwardly. As the arms move inward (to the right) they are positively forced together so as to insure full entry of pins 26c and 26d, and to fix the roll horizontally.

A web brake 38 is provided on top of the machine at the cutting region which engages the web so that after it is cut the portion below roll 16 will not fall back into the machine. This is a simple friction brake which allows forward movement of the paper when pulled toward the operator (leftward in Fig. 1).

Much improvement in web cutting is effected by keeping the web 14 fairly flat during cutting. To do this with tubular paper from rolls presents typical difficulty for such rolls because the web varies slightly in thickness transversely and longitudinally in an unpredictable manner.

The roller 32 is provided to rest on the web 14 and maintain tension thereon. To maintain a uniform pull across the web, the roll 32 is mounted in loose bearings 32a in arms 32b which arms are pivoted at 32c on rack 26. This looseness of bearings permits the roller 32 to pull uniformly on the vertical part 14a of web 14.

In order to maintain tension in web 14a, the roll 12 is prevented from overrunning due to acquired momentum and the weight of roll 32. A band 32c of leather belting is secured to one arm 32b as at 32d and passed over the adapter 26h and downwardly to an anchor 32e on arm 26a.

A groove 32f is provided in adapter 26h for this purpose. As the tube 32 drops down it pulls 32c tangent to the groove and stops rotation of the roll of tubing 12. However, when the operator pulls on the web as at 20, the tube 32 raises to release the band 32c and allow the roll 12 to turn as rapidly as desired. It stops instantly upon cessation of upward movement of web portion 14a. In this way the web 15 is maintained flat and in proper alignment at the top of the machine.

I claim:

1. In a machine for feeding a length of a sheet from a roll thereof, a first frame having opposite side members, a roll support frame comprising a pair of opposite side members hingedly mounted

at one end on said opposite side members for movement on said first frame, a transverse member slidably engaged with the other end of each side member, each side member being flexible to enable such member to be moved away from the other side member, and roll support means carried on each side member to support a roll of sheet material for rotation between said side members.

2. In a machine for feeding a length of a sheet from a roll thereof, a first frame having opposite side members, a roll support frame comprising a pair of opposite side members hingedly mounted at one end on said opposite side members for movement on said first frame, a transverse member slidably engaged with the other end of each side member, each side member being flexible to enable such member to be moved away from the other side member, roll support means carried on each side member to support a roll of sheet material for rotation between said side members, said support frame being movable into and out of supporting engagement with said first frame and stop means on said first frame limiting movement of said support frame with respect to said first frame and for retaining said support frame in roll supporting position.

3. In a machine for feeding a length of a sheet from a roll thereof, a first frame, a roll support frame comprising a pair of opposite side members hingedly mounted at one end for movement on said first frame, a transverse member slidably engaged with the other end of each side member, each side member being flexible to enable such member to be moved away from the other side member, a roll support means carried on each side member to support a roll of said sheet material for rotation between said side members, an arm hinged on each of said side members, and a rod extending transversely of said arms and engaged with and partially supported by a sheet fed from the supported roll.

4. In a machine for feeding a length of a sheet from a roll thereof, a first frame, a roll support frame comprising a pair of opposite side members hingedly mounted at one end for movement on said first frame, a transverse member slidably engaged with the other end of each side member, each side member being flexible to enable such member to be moved away from the other side member, roll support means carried on each side member to support a roll of said sheet material for rotation between said side members, an arm hinged on each of said side members, a rod extending transversely of said arms and engaged with a sheet from the supported roll, and brake mechanism mounted in one of said roll

support means and operated by one of said hinged arms to control rotation of the paper roll.

5. In a machine for feeding a length of a sheet from a roll thereof, a first frame, a roll support frame comprising a pair of opposite side members hingedly mounted at one end for movement on said first frame, a transverse member slidably engaged with the other end of each side member, each side member being flexible to enable the other end of said member to be moved away from the other side member and permit a roll to be inserted between said side members, and roll support means carried on each side member to support a roll of said sheet material for rotation between said side members.

6. In a machine for feeding a length of a sheet from a roll thereof, a first frame, a roll support frame comprising a pair of opposite side members hingedly mounted at one end for movement on said first frame, a transverse member slidably engaged with the other end of each side member, roll support means carried on each side member to support a roll of such sheet material for rotation between such members, each side member being flexible to enable said member to be moved away from the other side member, to admit a roll between said roll support means, said support frame being movable into and out of supporting engagement with said first frame, and stop means on said first frame limiting movement of said support frame with respect to said first frame and for engaging each side member to retain said support frame in roll supporting position.

7. A machine for feeding a length of a sheet from a roll thereof comprising a first frame, a roll support frame comprising a pair of opposite side members hingedly mounted at one end for movement on said first frame, a transverse member slidably engaged with the other end of each side member and permitting each side member to be flexed and moved away from the other side member to admit of insertion of a roll therebetween, roll support means carried on each side member to support a roll of such sheet material for rotation between said side members when said members are engaged with the transverse member, an arm hinged on each of said side members, a rod extending transversely of said arms and engaged with a sheet threaded from the supported roll, and brake mechanism mounted in one of said roll support means and operated by oscillation of said rod to restrain or to release the roll for rotation.
